ATTORNEY

UNITED STATES PATENT OFFICE.

JOHN C. H. LUBKEN, OF WESTMONT BOROUGH, PENNSYLVANIA.

MINING-CAR.

1,311,659.

Specification of Letters Patent. Patented July 29, 1919.

Application filed June 17, 1918. Serial No. 240,312.

To all whom it may concern:

Be it known that I, JOHN C. H. LUBKEN, a citizen of the United States, residing in the borough of Westmont, in the county of Cambria and State of Pennsylvania, (whose post-office address is Johnstown, Pennsylvania,) have invented certain new and useful Improvements in Mining-Cars; and I do hereby declare the following to be a full, 10 clear, and exact description, such as will enable others skilled in the art to which it appertains to make and use the same.

My invention relates to cars used in mining or other industries, and particularly to 15 those that are made up into trains and hauled by a motor, cable, or otherwise, and one of the objects of my invention is to provide a car that is well adapted to this service and constructed with particular reference 20 to withstanding the pulling and bumping shocks to which such cars are subjected.

My car body is preferably made of sheet or plate metal which is pressed into shape with a flat bottom and with a central longitudinal ridge formed integral in the bottom portion and projecting upwardly therefrom, the upper portions of the car sides being flaring and provided with a rounded bead at 25 their upper edges to strengthen and stiffen 30 the same, and provided with separate end pieces which are secured to the sides and bottom by flanges formed integral with said end portions so that in case of damage of any one portion, the damaged one alone need be 35 replaced.

One of the particular features of my invention relates to reinforcing the bottom by the insertion of a longitudinal sill of timber, inserted and fitted within the up-pressed 40 metal ridge of the car bottom and secured to the car bottom by rivets or bolts, the ends of the sill being provided with bumper blocks, preferably made of pressed steel and with a continuous draw-bar secured thereto, where- 45 by these cars, when formed into a train, have a substantially continuous draw-bar and center sill extending throughout the length of the train, thereby adapting them to fully 50 withstand any pulling or bumping shocks to which they may be subjected.

Having thus given a general description of my invention, I will now, in order to make the matter more clear, refer to the an-

nexed sheet of drawings, which forms part of this specification, and in which like characters refer to like parts:

Figure 1 is a top plan view of my improved mining car;

Fig. 2 is a side elevation of the mining car, with the right-hand portion of the car shown 60 in vertical sectional elevation on the longitudinal center line of the car;

Fig. 3 is a vertical transverse sectional elevation taken on the line III—III of Fig. 2;

Fig. 4 is a side elevation of one of the bumper blocks;

Fig. 5 is a top plan view of the bumper block; and

Fig. 6 is a top plan view of one of the 70 pressed metal spacing members.

Referring now to the characters of reference on the drawings: 1 represents the car body in general, 2 the sides thereof, the upper portions of which are shown as flaring 75 and provided with a reinforcing bead on the upper margin thereof, 3 is the car bottom, 4 is a central longitudinal ridge shown as of channel section formed integral with the bottom plate portion of the car body, 5 are 80 the ends of the car which, as shown, are provided with flanges whereby they are secured to the body portion, 6 are reinforcing plates on the inside of the car floor adapted to strengthen the same at and near the points 85 of application of the axles to which the load is transmitted, 7 are angles applied transversely to the bottom of the car to further strengthen and stiffen the same, 8 is a draw-bar composed of a flat bar of iron or steel 90 applied and secured to the top portion of the up-pressed center sill, as illustrated, and provided with holes 10, adapted to receive the coupling pins 11 and 12. These up-bent ends 9 of the continuous draw-bar are spaced 95 apart from the bumper so as to provide room for the coupling link between the same, as illustrated. A wooden sill 13 is inserted in the trough or opening formed by the up-pressed metal portion of the bottom and to 100 the ends of this the bumper members 14 are secured. The bumper, as illustrated, is formed preferably of pressed metal having coupling pin hole 15 and an end face 16, adapted to contact with the companion 105 bumper of the adjacent car when the same

come together and also provided with an upper flanged portion 17 and a bottom flange 18, the bottom flange being wider and provided with holes adapted to receive bolts, 5 as illustrated, to secure it to the metal end of the car. 19 is a pressed metal spacing member located between the bent-up end portion 9 of the metal draw-bar and the upper surface of the flange 17 of the bumper 10 block and all secured together by bolts, as shown, this spacing member being provided with the flanged edge 20, as illustrated.

On account of the addition of the wooden center sill to the bottom of the metal car 15 and preferably in the approximately rectangular space formed by the up-pressed longitudinal projection of the floor plate and by securing said wooden sill to the metal body, I provide a combination of wood and 20 metal which is very well adapted to give the necessary strength to the structure and to ably withstand any pulling or buffing stresses to which it may be subjected. The wooden sill to reinforce the metal structure 25 is particularly useful in withstanding heavy buffing stresses, as the wood has a certain amount of elasticity, but its modulus of elasticity is much lower than that of steel and its reactive effect is less on account of its 30 structure so that when a heavy shock comes upon the sill in the attempt to compress or buckle it, this shock is largely absorbed by the wooden sill and the reaction given back gradually to a much lesser extent. In view 35 of this, the addition of the wooden sill is particularly effective and has been so proven by actual use.

Although I have described and illustrated my invention in considerable detail, I do 40 not wish to be limited to the exact and specific details thereof as shown and described, but may use such modifications in, substitutions for, or equivalents thereof, as are embraced within the scope of my invention, or 45 as pointed out in the claims.

Having thus described by invention, what I claim and desire to secure by Letters Patent is:—

1. The combination with a metal car body 50 of a wooden longitudinal center sill partially surrounded by and secured thereto and adapted to strengthen and reinforce the same against stresses.

2. In a metal car provided with an up- 55 wardly projecting longitudinally extending central portion, a wooden sill seated within

said projection and secured to the adjacent metal construction.

3. A car body composed of metal plate provided with an upwardly and longitudinally 60 extending portion, a wooden center sill seated within the recess of said portion and secured to the car structure.

4. In a car body, a metallic floor plate provided with an integral portion projecting 65 therefrom and extending longitudinally of the car near the center thereof, a wooden center sill seated within the recess formed by said projecting portion and secured to the car structure.

5. A metal car body provided with a plate floor, the integral intermediate longitudinally extending portion of which projects therefrom in trough form, a wooden sill seated within said trough and secured 75 to the car structure.

6. A metal car provided with a wooden center sill extending longitudinally thereof, a pressed steel bumper plate on each end of said sill, said plate comprising a lower 80 flanged portion and an upper flanged portion which are substantially parallel, a bumper portion which is approximately at right angles to said flanges and means for securing same to the center sill and to the 85 car structure.

7. A metal car provided with a wooden center sill extending longitudinally thereof, a pressed steel bumper plate provided with 90 holes to receive the coupling pin, on each end of said sill, said plate comprising a lower flanged portion and an upper flanged portion spaced apart and substantially parallel, a bumper portion joining said flanges, and means for securing same to the 95 center sill and to the car structure.

8. In a metal car, a wooden center sill extending longitudinally thereof and projecting outwardly from the end portions, a pressed steel bumper plate secured on each 100 end of said sill and provided with holes to receive the coupling pin; means for securing same to the car structure; a longitudinally extending draw-bar secured to the car structure, the ends of same being offset and 105 spaced apart from said bumpers and means interposed between said draw-bar and said bumpers to maintain said spacing.

In testimony whereof I hereunto affix my signature.

JOHN C. H. LUBKEN.
